HAT LINING ATTACHING MACHINE

Louis Meylach and Leslie M. Page,
New York, N. Y.

Application January 16, 1937, Serial No. 120,848

5 Claims. (Cl. 223—22)

This invention relates to a machine for attaching a lining to a hat body by means of adhering the former to the latter, and its principal object is to provide a simple, efficient, and improved machine for this purpose, wherewith such work may be performed easily, rapidly, conveniently, economically, and without requiring particular skill.

Another object is to provide an apparatus for the above purpose, the inherent functioning of which will result in execution of an improved product.

Other objects and advantages will hereinafter appear.

15 In the accompanying drawing,—

Fig. 1 is a plan view of the machine of this invention.

Fig. 2 is a transverse-sectional elevation of the apparatus shown in Fig. 1.

20 The apparatus 1 comprises a machine base 2, a work performing element 3, operating mechanism 4, and a carrying lever 5. In the base 2 is formed a framing 6 which is configurated to the size of the hat body to be worked upon. Thus, the framing 6 is ovaline as shown in Fig. 1 to conform to the shape of the hat body, and is adapted to receive the body 7 in an inverted position and in the manner illustrated in Fig. 2. Within the framing 6 is located the element 3, comprising a 25 flat, metallic, tubular band 8, which extends parallel to the framing, is closed at one terminal 9 thereof, and has its opposite end portion 10 bent over as shown towards the centre of the framing, wherewith its opposite terminal 11 is secured to and 30 leads into a vertically disposed tubular rock-shaft 12, in the manner illustrated in Fig. 1. The band 8 has its exterior wall 13 provided with a series of perforations 14 facing the framing 6, while its interior wall 15 is lined with an electric heating 35 coil 16 which is enveloped by an asbestos lining 17. Links 18 are pivotally joined to lugs 19 forming part of the rock-shaft 12 and to lugs 20 forming part of the tubular band 8, which is flexible. Rocking of the shaft 12 in a clockwise 40 direction as viewed in Fig. 1, therefore, transmits action through the links 18 to expand the ovaline band 8 toward the framing 6, while rocking said shaft oppositely contracts the band away from the framing to the position shown in Fig. 2. The 45 shaft 12 is journaled in a hub 21 which forms part of the horizontal carrying lever 5 pivoted to a post 22 depending from the machine base 2, said lever being provided with a counterweight 23 and finger-knob 24, and the shaft is further journaled through a T-fitting 25 and provided at its extrem-

ity with an operating handle 26 keyed thereto at 27. A steam conducting pipe 28 is connected to the opening 29 of T-fitting 25 which is tapped at 30 to the lever 5, and the hollow shaft 12 is provided with an inlet 31 in alignment with the pipe 28. The hub 21 is surrounded by a heating coil 32 which is enveloped by an asbestos lining 33, and electric current fed by wires 34 and connecting conducting wires 35 energizes said coil as well as the coils 16.

10 For carrying out the process with this apparatus it is preferable to first prepare the hat lining 36, by utilization of a tape 37, made of duck or other suitable material and heavily impregnated with an adhesive substance, which is normally dry but becomes damp and very sticky when steam and heat is applied thereto. Said tape is secured to the rim of lining 36 by a line of stitching 38, as illustrated in Fig. 2.

15 Normally, the entire apparatus is elevated over and out of the framing 6, as indicated by the dash and dot lines, Fig. 2, the counterweight 23 maintaining the carrying lever 5 with all its depending parts in uplifted state. When it is desired to attach the hat lining to the hat body, the latter 20 is inserted into the framing 6, in the inverted position shown, then the lining 36 is placed within the body 7 in required location with its adfixed tape 37, and then the lever 5 is swung downwardly about its hinge 5a to its horizontal position to bring the element 3 within the framing 6 and level with the adhesive tape 37. The operative then turns the handle 26 in a clockwise direction, to rock the shaft 12 and expand the band 8 into a pressing contact against the rim 30 of lining 36, tape 37, intervening hat body 7, and the framing 6, and simultaneously the inlet 31 is turned into registry with the opening 29 of fitting 25, whereupon steam is conducted from pipe 28, through hollow shaft 12, into the tubular 35 band 8, and from the perforations 14 to the compressed hat lining 36, tape 37, and hat body 7, in which manner the latter become steamed and heated, and an efficient cementation and complete assemblage of the lining and hat body are 40 effected. The lever 5 may be then elevated to conveniently remove the assembled hat and lining from the machine.

45 The coils 32, 16 continually impart heat to the steam passageways and the band 8, whereby these 50 parts are maintained dry hot for the efficient working of the process. An adjustable stop is provided for the lever 5, to alter the setting of the level elevation of the element 3 within the framing 6, said stop comprising a projection 39 55

depending from the base 2 and a plate 40 vertically slidable therealong by means of a bolt 41 passing through registering slots 42 of both parts, as shown in Fig. 2, said bolt being fastened upon 5 the elevational setting of the plate 40 against which the lever 5 abuts upon its downward throw.

Any other method, than by the tape 37 shown, may be resorted to for adhering the lining to the 10 hat body, and should any adhesive substance be utilized which does not require any steam, the latter may be eliminated and the apparatus may be otherwise operated to impart requisite heat by coils 32, 16 to the expanding pressure-band 8. 15 If an adhesive substance should be resorted to which does not require any heat, the apparatus may be operated without energizing the coils 32, 16.

Variations may be resorted to within the scope 20 of the invention, and portions of the improvements may be used without others.

Having thus described our invention, we claim:

1. An apparatus for assembling a hat lining with a hat body by adhesiveness having the combination of a body retaining framing configurated to fit the body, an element having a chamber with perforated walls paralleling said framing and expansible and contractible toward and away from the framing, means for actuating said walls, 30 means to feed steam to said chamber, and a valve in said steam feeding means operated by said actuating means to admit steam to said chamber upon expansion of said walls and to shut off the steam upon contraction of the walls.
- 35 2. An apparatus for assembling a hat lining with a hat body by adhesiveness having the combination of a body retaining framing configurated to fit the body, an element having a chamber with perforated walls paralleling said framing and expansible and contractible toward and away from the framing, means for actuating said walls, means to feed steam to said chamber, and a valve in said steam feeding means to admit steam
- 40

to said chamber upon expansion of said walls and to shut off the steam upon contraction of the walls.

3. An apparatus for assembling a hat lining with a hat body by adhesiveness having the combination of a body retaining framing configurated to fit the body, an element having a chamber with perforated walls paralleling said framing and expansible and contractible toward and away from the framing, a rock shaft located centrally of said element, a plurality of links joining said shaft with said walls for actuating the walls, means to feed steam to said chamber, and a valve for controlling said feed. 5

4. An apparatus for assembling a hat lining with a hat body by adhesiveness having the combination of a body retaining framing configurated to fit the body, an element having a chamber with perforated walls paralleling said framing and expansible and contractible toward and away from the framing, means for actuating said walls, means to feed steam to said chamber, a valve in said steam feeding means to admit steam to said chamber upon expansion of said walls and to shut off the steam upon contraction of the walls, and means to heat said element. 10

5. An apparatus for assembling a hat lining with a hat body by adhesiveness having the combination of a body retaining framing configurated to fit the body, said framing adapted to receive the hat body invertedly, an element having a chamber with perforated walls paralleling said framing and expansible and contractible toward and away from the framing, means for actuating said walls, means to feed steam to said chamber, a valve in said steam feeding means to admit steam to said chamber upon expansion of said walls and to shut off the steam upon contraction of the walls, and means to elevate said element 30 out of said framing and to restore it to operative 35 position within said framing. 40
